DISPENSER FOR TISSUES

Victor Schadenburg, Grand Rapids, Mich.

Application March 25, 1954, Serial No. 418,554

1 Claim. (Cl. 221—46)

This invention relates to a holder designed to provide a container for a small package of tissue papers whereby it may be kept in a convenient place under the hood of an automobile or truck.

It is the practice of truck drivers and many passenger car drivers to check the oil level of their crankcase frequently. Many times this is done along the highway rather than at a service station and, thus, there is available no convenient means for wiping the dip stick or the driver's hands. Cloths kept for wiping the windshield and mirrors cannot be used because the oil will contaminate the cloth. Further, drivers do not like to keep an oily cloth in the passenger compartment or cab.

This invention is designed to provide an inexpensive means for holding a small packet of tissue paper under the hood of the vehicle and at the same time to provide an easy means for dispensing this paper as needed sheet by sheet.

These and other objects of this invention will be readily understood upon reading the specification and the accompanying drawings.

In the drawings:

Fig. 1 is a fragmentary, partially broken, side elevation view of a vehicle showing my invention mounted on the fire wall.

Fig. 2 is a front elevation view of my invention with the packet partially inserted.

Fig. 3 is a plan view of my invention with a packet of tissue papers seated within the container.

Fig. 4 is a fragmentary, sectional view taken along the plane IV—IV of Fig. 2.

Fig. 5 is a front elevation view of a modified form of my invention.

Fig. 6 is a plan view of the container appearing in Fig. 5.

Fig. 7 is a fragmentary, sectional view taken along the plane VII—VII of Fig. 5.

Referring specifically to the drawings, the numeral 10 indicates a vehicle having a fire wall 11. A tissue container 12 is secured to the fire wall where the tissues will be readily available once the vehicle's hood has been opened.

In the form of my container illustrated in Figs. 2, 3 and 4, the body of the container may be made from any suitable material such as metal or plastic. The container is generally parallelepiped in form, having a front panel 20, a back panel 21, sides 22 and a closed bottom 23. The top of the container 12 is open. The front panel 20 has a vertically extending slot 24. The length of the slot 24 constitutes a major portion of the height of the container. The slot 24 has a widened portion 25 at the center. The slot 24 serves as a means of access to the tissue paper within the container. When the container is mounted vertically, the paper is dispensed through the front face. The back panel 21 is provided with a pair of countersunk openings for receiving the mounting screws 26. The mounting screws are accessible through

2

the opening 24 and secure the container to its supporting structure such as the fire wall 11.

In the modified form of my container shown in Figs. 5, 6 and 7, the container 12a is of generally rectangular configuration having a front panel 30, a back panel 31 and sides 32. The front panel 30 has a vertically extended slot-like opening 33 identical to the opening 24 in the container 12. The top of the container is open. The bottom of the container 12a is also open except for a pair of arms 34 extending from the back panel to the front panel. Each of the arms 34 has an upwardly turned lip 35 which abuts the front panel 30 and is preferably secured thereto by suitable means such as spot welding.

The container 12a is designed to be formed from a single sheet of metal. The sheet is bent to the desired shape and the ends of the sheet are overlapped to provide a joint 36 extending up the center of the back panel 31. The two parts of the joint are held together by the mounting screws 26 which extend through both flanges forming the back panel of the container.

Although the container is described as secured to the fire wall 11, it may be secured to any other suitable structure in the engine compartment such as to the interior face of the fender. The container should be located within convenient reach of the operator when the operator is manipulating the crankcase dip stick.

The container is designed to be mounted on a vertical or substantially vertical wall with the open end up. By so mounting the container the necessity of providing means for preventing accidental discharge of the packet 40 through the open end is eliminated.

The container is designed to hold a conventional, small packet of tissue paper containing about twenty sheets. These packets are of the continuous dispensing type whereby the removal of one sheet automatically withdraws the end of the next sheet from the packet leaving it ready to be easily grasped. The conventional slot 41 provided in such packets is opened and the packet 40 inserted through the open top of the container. The tissue paper is not removed from its original packet, the entire packet being inserted into the container. The packet's slot 41 aligns with the openings 24 or 33, providing access to the tissue paper through the slot. By this means, the tissue papers can be withdrawn sheet by sheet until the package is exhausted. At this time the empty packet or casing is removed and replaced by a new one.

The widened central portion 25 of the slotted opening 24 makes it easy for the driver to grasp the end of a sheet of tissue paper projecting from the packet 40 through the slot 41.

The bottom panel 23 or the arms 34 provide a positive stop for the packet 40. They assure vertical alignment between the openings 24 or 33 and the slot 41.

The size of the container is such that the packets will slip easily in and out of the container but with enough friction to prevent them from escaping from the container as the result of jarring and vibration incident to the operation of the vehicle. The container positively holds the tissue packet and assures a supply of tissue for the operator whenever he wishes to check his oil or do any other thing around the engine. The design of the container is such that it is economical to construct and easy to install and provides a maximum of convenience to the operator.

Having described my container, that which I claim to be my invention is set forth in the following appended claim.

In combination with an upwardly extending wall of a vehicle engine compartment, a holder-dispenser for a packet of tissues; said holder-dispenser having a vertically elongated one-piece tubular body; said body hav-

ing a front panel, a pair of side panels and a pair of rear panel portions each of greater width than one-half the width of said dispenser body; said rear panel portions overlapping at the center of said dispenser body and provided in the area of said overlap with aligned openings; a fastener element received through each of said aligned openings engaging said wall of said vehicle for securing said dispenser body thereto and joining said rear panel portions together for completing the assembly of said dispenser body; said front panel having a centrally disposed vertically elongated panel aperture adapted to provide access to a packet of tissues seated in said dispenser body; said front aperture being enlarged in the center and aligned with said openings in said rear panel portions; the upper end of said dispenser body being open for reception of a packet of tissues therethrough; said dispenser body having a bottom panel integral with one of the vertically extending panels of said dispenser

5

body; said bottom panel being smaller than the cross sectional area of said dispenser body for partially closing the bottom end thereof.
